US0D1085856S

(12) **United States Design Patent** (10) **Patent No.:** **US D1,085,856 S**
(45) **Date of Patent:** **** Jul. 29, 2025**

(54) **APPARATUS FOR FIXING**

(71) Applicant: **Hefei Chu**, Zhejiang (CN)

(72) Inventor: **Hefei Chu**, Zhejiang (CN)

(**) Term: **15 Years**

(21) Appl. No.: **29/905,375**

(22) Filed: **Oct. 19, 2023**

(51) LOC (15) Cl. **08-08**

(52) U.S. Cl.

USPC **D8/394**

(58) **Field of Classification Search**

USPC D6/513, 553, 567; D8/14, 71, 72, 73, D8/349, 354, 355, 363, 373, 380, 382,

(57) **CLAIM**

The ornamental design for an apparatus for fixing, as shown and described.

DESCRIPTION

FIG. 1 is a first perspective view of an apparatus for fixing showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the apparatus for fixing that form no part of the claimed design.

1 Claim, 8 Drawing Sheets
